UNITED STATES PATENT OFFICE.

ERNEST ALBERT INGOLD, OF LONDON, ENGLAND, ASSIGNOR TO (MESSRS.) W. & C. PANTIN, OF LONDON, ENGLAND.

WIRE BINDING OR TYING APPARATUS.

Application filed May 5, 1924. Serial No. 711,269.

To all whom it may concern:

Be it known that I, ERNEST ALBERT INGOLD, a subject of the King of Great Britain, residing in London, England, have invented certain new and useful Improvements in Wire Binding or Tying Apparatus, of which the following is a specification.

This invention relates to apparatus for binding or tying wooden or other boxes, bales or the like with hoops of wire the ends of which are twisted together by causing them to overlap and gripping the overlap with a rotary twisting device by means of which the two wires are twisted together on either side of the grip. Such an apparatus is described by the present applicant in United States Patent No. 1,486,396.

Hitherto one end of the wire has been gripped fixedly by means of a pair of gripping jaws or clips so that the distance between that gripping point and the adjacent twisting pinion should there be more than one twisting pinion was invariable during the twisting operation. As this part of the wire tends to shorten owing to the twist imposed upon it, unless the wire used was of a comparatively soft and extensible material breakages of the wire at this point were common, and the principal object of the present invention is to enable binding wires of hard and comparatively inextensible steel or iron to be used. Accordingly, by the present invention, the gripping jaws or clips whereby the fixed end of the wire is secured are so mounted that at a predetermined phase of the twisting operation they permit the point of grip, and with it the wire, to move inwardly towards the twisting pinion sufficiently to avoid any tendency of the wire to be broken.

According to the present invention the wire is gripped between a normally fixed clip and a pivoted clip preferably having an eccentric engaging edge which is also preferably serrated, and when the wire is placed in the correct position prior to twisting it is gripped by turning the pivoted clip about its pivot by hand. The other clip is mounted to slide outwardly away from the wire and its fellow clip, but is normally held up to its work by means of a stop which, at a predetermined phase of the twisting operation, is displaced so as to permit the sliding clip to yield and there-

by permit the wire, and with it the pivoted clip, to be drawn forwards towards the twisting pinion. A blade spring operating upon the sliding clip serves to restore it to its normal position.

The invention is illustrated in the accompanying drawings, wherein Fig. 1 is a plan view, with parts omitted, of a wire binding or tying machine of the general character described in United States Patent No. 1,486,396, in which the overlapping parts of the loop of wire passed around a package are twisted together by means of two oppositely rotating twisting pinions; Fig. 2 is a section of the same on line 2-2 of Fig. 1; Fig. 3 a section on line 3-3 of Fig. 2; and Figs. 4 and 5 are sectional plans on an enlarged scale of the gripping members in two different positions.

As shown in these drawings A represents that end of the wire which has hitherto been gripped fixedly by means of a pair of gripping jaws, while B is the other end of the wire which, as hitherto, is fixed in a gripping device C which is movable longitudinally so as to tension the loop of wire around the package.

According to the present invention the end A of the wire is gripped between a normally fixed clip D and a pivoted clip E, one or both of these being preferably provided with serrated edges which, in the case of the pivoted clip, are eccentric with respect to the pivot E'. The clip D is secured to a block or slide F which is guided for longitudinal movement in a suitably formed guide G secured to or forming part of the frame of the machine. The slide F carrying the normally fixed clip D is held up to its work by means of a lever H fulcrumed in a bracket on the frame, one end H' of this lever engaging a recess in the slide F, while the other end has pivotally mounted upon it a bar I which normally rests upon a positioning stop J and is acted upon by a cam K' carried by one of the driving shafts K of the twisting pinions, and the free end of this bar abuts against an arresting stop L adjustably secured to the frame.

The cam K' comes into action at a predetermined point of the twisting operation to lift the bar I and thereby establish a clearance between the end of the bar and the arresting stop L. This permits the le-

ver H to turn upon its fulcrum and thereby, under the tension of the wire which is being twisted, enables the slidably mounted clip D to be displaced outwardly against 5 the action of a suitable spring, as for example a blade spring F' acting upon the rear end of the slide F.

Initially, i. e. before the twisting operation begins, the end A of the wire is clipped 10 as shown in Fig. 4 and as, during twisting, that part of the wire between the clips D, E and the adjacent twisting pinion tends to shorten, the pull upon the wire forces the clip D rearwards and at the same time turns 15 the clip E upon its pivot E' until finally the parts assume the position shown in Fig. 5.

As shown in Fig. 2, the lower side of the 20 bar I is notched as indicated at I' so that the lift of the bar I will cease when the cam K' comes into register with this notch. An auxiliary return spring I² acting upon, 25 the pivoted bar I and tensioned by the lifting of the latter ensures the bar being restored to its normal position against the positioning stop J when the pivoted clip E is displaced manually or automatically to release the cut-off end of the wire.

To allow for wires of different diameters 30 to be used the pivoted clip E, or alternatively the normally fixed clip D, is so mounted that its distance from the wire and from its cooperating clip can be adjusted as desired. As shown in the drawings the normally fixed clip D is slotted to permit of its longitudinal adjustment on the slide F, a grub-screw through the end of the latter determining the position of the clip with 35 respect to the slide and, in conjunction with the screws passing through the slot holes and screwed into the slide, holding the clip 40 in position.

Having thus described the nature of the 45 said invention and the best means I know of carrying the same into practical effect, I claim:-

1. In an apparatus for twisting together the overlapping ends of a loop of wire encircling a package, a gripping device for

securing one end of the wire during the 50 twisting operation comprising a pivotally movable clip, a transversely movable clip cooperating therewith to hold the wire, a stop normally preventing transverse movement of the latter clip, and means operating to withdraw the stop at a predetermined phase of the twisting operation. 55

2. An apparatus according to claim 1 said stop comprising a lever pivoted upon the 60 apparatus frame, a bar pivoted upon said lever and an arresting stop secured upon the apparatus frame and cooperating with said bar to prevent movement of the pivoted lever.

3. In an apparatus for twisting together 65 the overlapping ends of a loop of wire encircling a package, a gripping device for securing one end of the wire during the twisting operation comprising a pivotally movable clip, a transversely movable clip 70 cooperating therewith to hold the wire, a stop comprising a lever pivoted upon the apparatus frame, a bar pivoted upon said lever, an arresting stop secured upon the apparatus frame cooperating with said bar to prevent movement of the pivoted lever and means for displacing said pivoted bar from engagement with said arresting stop at a predetermined point in the twisting 75 operation, said means comprising a cam carried by one of the driving shafts. 80

4. In an apparatus for twisting together the overlapping ends of a loop of wire encircling a package, a gripping device for 85 securing one end of the wire during the twisting operation comprising a pivotally movable clip, a transversely movable clip cooperating therewith to hold the wire, one of said clips being adjustably mounted so that its initial distance from its cooperating clip can be varied, a stop normally preventing movement of the transversely movable clip, and means operating to withdraw the stop at a predetermined phase of the 90 twisting operation. 95

In testimony whereof I have signed my name to this specification.

ERNEST ALBERT INGOLD.
